UNITED STATES PATENT OFFICE.

MARCELLUS B. WILLCOX, OF CLEVELAND, OHIO.

DESIGN FOR A LAMP-HOOK.

SPECIFICATION forming part of Design No. 12,284, dated May 24, 1881.

Application filed April 16, 1881. Term of patent 14 years.

To all whom it may concern:

Be it known that I, MARCELLUS B. WILLCOX, a citizen of the United States, residing at Cleveland, in the county of Cuyahoga and

5 State of Ohio, have invented and produced a new and original Design for Lamp-Hooks, of which the following is a specification, reference being had to the accompanying drawings, forming part thereof.

10 Figure 1 is an isometric view of my newly designed lamp-hook. Fig. 2 is a view in cross-section of the same through the line *x y* of Fig. 1. Fig. 3 is an edge view.

Heretofore lamp-hooks have been made having raised edges and raised tracery for the purpose of polishing. This hook is made elliptical or oval in form in cross-section, as shown in Fig. 2.

15 In the drawings, A represents the body of the hook, having its edges B rounding. Upon 20 its sides it may or may not be ornamented with

tracery. I also provide a hexagonal bearing, C, to be either removably or permanently attached to this hook, and which, when the hook is in position, rests against the ceiling.

25

What I claim is—

1. The design for lamp-hook elliptical in cross-section and ornamented with tracery upon its sides, substantially as herein shown and described.

30

2. The design for lamp-hook, elliptical in cross-section and ornamented with tracery upon its sides, in combination with the hexagonal plate C, substantially as and for the purposes shown.

35

In testimony whereof I have signed my name to this specification in the presence of two subscribing witnesses.

MARCELLUS B. WILLCOX.
